UNITED STATES PATENT OFFICE

114,441

DESIGN FOR A GARMENT CLASP

Frederick G. Deming, Rochester, N. Y., assignor
to Hickok Manufacturing Company, Inc.,
Rochester, N. Y., a corporation of New York

Application March 1, 1939, Serial No. 83,274

Term of patent 3½ years

To all whom it may concern:

Be it known that I, Frederick G. Deming, a citizen of the United States, residing at Rochester, in the county of Monroe and State of New York, have invented a new, original, and ornamental Design for Garment Clasps, of which the following is a specification, reference being had to the accompanying drawing, forming part thereof.

I claim:

The ornamental design for a garment clasp, as shown.

FREDERICK G. DEMING.
